UNITED STATES PATENT OFFICE.

GEORGE W. HARER AND JACOB J. BURRI, OF CHICAGO, ILLINOIS.

GRAIN-CAR DOOR.

Application filed December 22, 1924, Serial No. 757,530. Renewed December 3, 1927.

This invention relates to doors especially adapted for use in grain cars.

Briefly stated, an important object of this invention is to provide a grain car door having upper and lower panels which may be opened separately for loading or unloading the car.

A further object of the invention is to provide simple means whereby either the door or the movable panels of the same may be securely locked in an adjusted position so as to withstand the pressure of the grain.

A further object is to provide a grain car door which may be easily operated, which is durable in use, and cheap to manufacture.

Other objects and advantages will be apparent during the course of the following description.

20 In the accompanying drawings forming a part of this application and in which like numerals are employed to designate like parts throughout the same,

Figure 1 is a side elevation of the improved grain car door in use;

Fig. 2 is a perspective of the upper panel of the door;

Fig. 3 is a perspective of the lower panel of the door;

30 Fig. 4 is a fragmentary perspective of the door frame and associated elements;

Fig. 5 is a detail longitudinal sectional view through the car illustrating the improved door therein;

35 Fig. 6 is a vertical transverse sectional view taken on line 6-6 of Fig. 5;

Fig. 7 is a horizontal sectional view taken on line 7-7 of Fig. 5;

Fig. 8 is a sectional view through a clamping device embodied in the invention.

Fig. 9 is a side elevation of the clamp with one section of the same removed.

In the drawings, wherein for the purpose of illustration is shown a preferred embodiment of the invention, the numeral 5 generally designates a door adapted to extend over the opening in a grain car 8, the said grain car being provided with a housing or casing 9 for the reception of the door when it is desired to either load or unload the car.

It will be seen that the upper end or rather the top of the door is provided with hangers 10 which operate on a track 11 extending for

the major portion of the length of the housing for the reception of the door and constituting a supporting means for the door. It will be understood that any suitable means may be employed for slidably mounting the door.

The door frame 5' consists of a U-shaped member having a pair of stiles, the inner sides of which are provided with grooves 15 for the reception of the edge portions of upper and lower panels 16 and 17, respectively. When the panels 16 and 17 are in their normal positions they overlap about six inches as illustrated in Fig. 6 and, therefore, have substantially grain tight contact with each other. The bottom connecting 70 member of the door frame is provided with a strip 144 having its upper surface inclined to shed the grain and thereby prevent the grain from being carried into the housing.

The lower panel 17 is provided with a 75 pair of racks 20 engaged by gears 21. The gears 21 are mounted upon shafts 22 carried by a cross bar or strip 23. It will be seen by reference to Figs. 5 and 7 that the gears 21 are engaged by gears 25 and 26, the 80 gear 25 being mounted upon a shaft 27 while the gear 26 is mounted upon a shaft 28. The shaft 27 may be provided with a squared or flat-sided socket for the reception of the attaching portion of a crank 30 by means 85 of which the gears 21 may be turned for raising and lowering the lower panel 17. It is believed to be obvious that the manual turning of the crank will result in either the up or down movement of the lower panel 17. 90 The outer portions of the shafts 22 are engaged by washers 31 which hold the shafts against endwise movement and these washers are connected to the shafts by machine screws 34 or other suitable means. Machine 95 screws or other suitable means may be employed to hold washers 35 in place on the shafts 27 and 28. This arrangement insures proper mesh of all of the gears of the organization.

The cross member 23 may be provided with one or more pawls 37 to engage in notches 38 in one or more of the racks 20 so as to hold the lower panel in an adjusted position. It will be seen that the pawl 37 is somewhat in the nature of a lever pivoted intermediate the ends thereof as shown at 40 and having its rear terminal portion ex-

tending beyond the lower edge of the fixed cross bar 23 so that the same may be manually engaged and moved to its inoperative position.

5 In carrying out the invention the end portions of the cross bar 23 are secured by screws or other fastening devices 41 in recesses 42 in the intermediate portions of the stiles of the door.

10 The upper panel 16 is provided with brackets 50 adjacent the opposite edges thereof and chains 51 are connected to these brackets and are trained over pulleys 52. The chains 51 have their lower terminal portions trained about a drum 54 carried by the fixed cross bar 23. More specifically, the drum may be said to be a part of a shaft rotatably connected to the cross bar 23 and having annular shoulders or washers 56 and 20 58 by means of which endwise movement of the drum is prevented. The other portion of the rotatable member 54 is provided with a squared socket 60 for the reception of the attaching portion of the crank 30 so that 25 the crank may be quickly connected to the drum for turning the same and lowering the upper panel.

Fig. 5 illustrates that a ratchet wheel 66 may be secured in any suitable manner on 30 the drum and is engaged by a pawl 67 pivoted to the cross bar 23 and adapted to hold the ratchet wheel and consequently the drum in a set position.

The upper portion of the panel 16 and 35 the top rail of the door are provided with lugs 69 having longitudinally extending openings adapted for alinement for the reception of a pin 70 by means of which the panel may be locked in its closed position.

40 The door is, of course, movable into the casing or housing so as to permit the loading or unloading of the car or one or both of the panels may be moved to open position by the aid of the crank. It might be stated 45 that when it is desired to start the unloading of the car the lower section is raised to allow some of the grain to be discharged and thereby relieve the pressure of the grain on the door. When sufficient grain has been 50 removed to relieve the pressure on the door the door is moved to open position. When the door is returned to closed position it will engage a stop 75.

The cross bar 23 may be provided with 55 a hood or housing 79 to extend over the gears and protect the same from dust and at the same time prevent the clothes or hands of the operator from coming in contact with the gears accidentally.

60 Figs. 8 and 9 illustrate that the door casing may be provided with a two-part sleeve 90 to receive an arm 91 having one end provided with an eccentric or cam 92 adapted to clamp the door in position. The 65 arm 91 is provided with a radial lug 94

positioned in a spiral slot 95 in the sleeve 90 so that when the arm 91 is turned by the crank 96 on the outer end of the same the arm will be moved longitudinally. That is to say, the arm will be moved longitudinally 70 at the same time it is turned so as to move the eccentric either to operative or inoperative position according to the direction in which the same is manually turned.

Having thus described the invention, what 75 is claimed is:

1. A grain car door comprising a frame, a cross bar carried by the frame, gears carried by the cross bar and having engagement with each other, a panel slidably carried by the frame and having racks adapted to engage certain of said gears, a crank having connection with one of said gears and adapted to be turned to move said panel vertically, and means supporting the door frame and the said parts carried thereby for horizontal movement as a unit to completely open or completely closed position.

2. A grain car door comprising a frame, a pair of panels slidably carried thereby, motion transmitting means carried by the frame and one of the panels whereby the panel having the motion transmitting mechanism may be raised and lowered, means carried by the frame and the other panel for raising and lowering the other panel, and means whereby the frame and the said parts carried thereby may be moved as a unit to open position to completely expose the opening the door is adapted to close.

3. A grain car door comprising a frame, panels slidably carried by said frame and having their adjacent portions overlapped when the panels are in closed position, a cross bar connected to said frame and extending across the frame at the point where the panels overlap, motion transmitting mechanism carried by said cross bar and one of said panels, a second motion transmitting mechanism connected to said cross bar and the other panel, and means whereby the frame and the said part carried thereby may be moved to open position to completely expose the opening the door is adapted to close.

4. A grain car door comprising a frame having its inner sides provided with grooves, panels extending into said grooves and having their adjacent portions overlapped, a cross bar connected to the sides of said door frame, gears carried by said cross bar, racks carried by one of said panels and engaged with certain of said gears, means whereby said gears may be turned for moving one of said panels vertically, manually controlled means for moving the other panel vertically and means whereby the frame and the said parts carried thereby may be moved to open position to completely expose the opening the door is adapted to close.

5. In a grain car, the combination of a 130

side wall having an opening, a door adapted to close said opening, a sleeve extending through said side wall and having a spiral slot, an arm extending through said sleeve and having a radial lug received in said slot whereby the turning of the arm results in the longitudinal movement of the arm, and a cam arranged on the inner end of said arm and adapted to engage said door to hold the same in a set position.

6. In a grain car, the combination of a side wall having an opening, a door adapted to close said opening, a sleeve extending

through said side wall and having a spiral slot, an arm extending through said sleeve and having a radial lug received in said slot whereby the turning of the arm results in the longitudinal movement of the arm, a cam arranged on the inner end of said arm and adapted to engage said door to hold the same in a set position, and a crank on the outer end of said arm.

In testimony whereof we affix our signatures.

GEORGE W. HARER.
JACOB J. BURRI.
